PRESERVING JAR CAP AND INDICATOR

Roman B. Bukolt, Stevens Point, Wis.

Application December 14, 1934, Serial No. 757,575

2 Claims. (Cl. 215—43)

The invention relates to a new and improved cap for the usual glass jars used for the preservation of fruits, vegetables or other foodstuffs which must be sealed hot with all air excluded for perfect preservation.

The principal object of the invention is to provide an exceptionally simple and inexpensive cap of unusual advantage, in that it will indicate in a novel way when it has been tightened to the proper extent, will indicate whether all air has been evacuated from the jar before sealing, and will indicate at all times after the jar is sealed, whether air is leaking into it or any gas is forming within, the cap being therefore of inestimable value in the preservation of foodstuffs.

With the foregoing and other objects in view which will become apparent as the description proceeds, the invention resides in the novel subject matter hereinafter described and claimed, description being accomplished by reference to the accompanying drawing.

Figure 1 is a vertical sectional view showing one form of the invention, showing the position of the cap top plate prior to sufficient tightening of the cap.

Figure 2 is a view similar to Fig. 1 but illustrating the manner in which the top plate of the cap snaps to an upwardly bowed position when the cap has been sufficiently tightened.

Figure 3 is another sectional view illustrating the top plate of the cap in the final downwardly bowed position to which it is forced after cooling of the jar contents, in which position it will remain unless air enters the jar or gas is generated therein.

Figure 4 is a sectional view showing a different form of the invention.

The cap shown in Figs. 1, 2 and 3 comprises a threaded side wall 5 to engage the usual threaded neck 6 of a preserving jar 7, a resilient lever-and-toggle-action snap disk or top plate 8 operatively connected with said side wall to snap from a normal downwardly bowed position (Fig. 1) to an upwardly bowed position (Fig. 2) and to a final downwardly bowed position (Fig. 3), and a gasket 9 of rubber or the like engaging the lower side of the peripheral portion of said disk to rest on the jar neck. Both the side wall 5 and the snap disk 8 are of course formed from suitable gage sheet-metal, and cold-rolled metal is preferred.

The disk 8 may be lightly peened or otherwise treated on its sides to radially expand the metal, causing said disk to snap in either direction past a central plane. The disk is so shaped that its peripheral portion 10 inclines upwardly and out-

wardly when said disk is in its normal downwardly bowed position and in fact said peripheral portion remains inclined in any position of the disk. When the cap is applied to a jar and is tightened to the proper extent for effective sealing, the 5 pressure of the gasket 9 against the peripheral disk portion 10 causes the disk 8 to snap from its normal downwardly bowed position (Fig. 1) to an upwardly bowed position (Fig. 2), thus indicating that the cap has been tightened to the 10 proper degree and tightening should always be effected until the disk snaps to its upwardly bowed position.

Assuming that the jar is completely filled with hot contents at the time of applying the cap, the 15 jar is set aside for cooling after the disk 8 snaps to the position of Fig. 2. Later when the jar contents have cooled somewhat and have consequently created a partial vacuum in the jar, the disk 8 is pushed downwardly by hand to the position 20 seen in Fig. 3. If the disk will remain in this position, it shows that a perfect seal has been effected, for only a partial vacuum within the jar will hold the disk in the depressed position 25 of Fig. 3. Therefore, if this disk will not stay depressed, it indicates that all air was not evacuated and the preserving process must be repeated. After the jar has been finally sealed with the disk 8 remaining in the position shown in Fig. 3, at 30 any time, this disk will show whether said jar is remaining properly sealed and will also indicate the condition of the contents. If at any time, the disk 8 occupies an upwardly bowed position, it shows either that air has been leaking into the 35 jar or that gas is being generated within, and proper steps can be taken to rectify the cause of the trouble.

When the jar is inverted and the weight of the contents is consequently supported by the 40 disk 8, an upward blow on the rim of the cap or striking this rim downwardly upon some object, will cause the disk to snap again to the position shown in Fig. 2, allowing opening of the jar with comparative ease. As long as the disk is held in 45 lowered position by the vacuum within the jar, it compresses the gasket 9 against the jar neck with extreme force to provide an unusually effective seal.

In the construction illustrated in Figs. 1 to 3, 50 the disk 8 and the side wall 5 are separate from each other and said side wall is provided with an inwardly turned flange 11 which overlies and rests upon the disk at the extreme edge of the latter, providing a fulcrum upon which the disk 55

moves relatively to the wall 5, during its snap action.

The center of the disk 8 is preferably provided with an upwardly stamped portion 12 showing the point at which the disk must be pressed to move it to its final position (Fig. 3).

In Fig. 4, a disk 8' corresponding to the disk 8 is integrally joined to the side wall 5' by a continuous yieldable bead 13. The peripheral portion 10' of this disk 8' co-acts with the gasket 9' in the same manner that the disk portion 10 above described cooperates with the gasket 9.

In both forms of the invention, the operative connection between the peripheral edge of the snap disk or top 8 and the side wall 5, is such that said disk or top may fulcrum about said peripheral edge as a hinge or pivot when said disk or top is moved from one bowed position to another. Furthermore, the disk is sufficiently stiff to actually pry downwardly upon the gasket 9 when the former is moved to downwardly bowed position, thus creating such a lever-action on said gasket as to forcibly compress the same in a fluid-tight manner.

It will be seen from the foregoing that novel provision has been made for carrying out the objects of the invention and while the details disclosed may be considered as preferred, it will of course be understood that minor variations may be made within the scope of the invention as claimed.

I claim:

1. A preserving jar cap and indicator comprising a side wall having means to engage a jar neck and move the cap downwardly when said cap is turned, a concavo-convex spring-metal snap-disk having a peripheral fulcrum connection with said wall and occupying an upwardly bowed position when the cap is tightened, and a gasket on the lower side of the peripheral por-

tion of said disk for compression upon the jar neck when the cap is tightened, said disk having sufficient radial stiffness to pry downwardly about said fulcrum connection when said disk is forced to a downwardly bowed position after cap 5 tightening, said disk thereby exerting a lever action which forcibly compresses said gasket, said disk when occupying said downwardly bowed position being so tensioned that it cannot remain in said downwardly bowed position unless held 10 therein by vacuum within the jar.

2. A preserving jar cap and indicator comprising a side wall having means to engage a jar neck and move the cap downwardly when said cap is turned, a concavo-convex spring- 15 metal snap disk having a peripheral fulcrum connection with said wall, said disk being tensioned to fulcrum about said fulcrum connection and snap to and remain in either an upwardly bowed position or to a downwardly bowed position prior 20 to cap application, said disk occupying said downwardly bowed position prior to tightening of the cap on the jar, and a gasket on the lower side of the peripheral portion of said disk for compression on the jar neck upon cap tightening, the 25 tension of said disk being such that the upward pressure of said gasket when the cap is tightened will upwardly snap said disk about said fulcrum connection to said upwardly bowed position, said disk having sufficient radial stiffness to pry 30 downwardly about said fulcrum connection and forcibly compress said gasket when said disk is again downwardly snapped to a final downwardly bowed position; said disk when occupying said final downwardly bowed position being so 35 tensioned that it cannot remain in said final downwardly bowed position unless held therein by vacuum within the jar.
